SOOT BLOWER

Carl Axel Arvid Westerberg, Djursholm, Sweden,
assignor to Aktiebolaget Superior, Stockholm,
Sweden, a joint-stock company of Sweden

Application August 20, 1932, Serial No. 629,727
In Sweden August 21, 1931

4 Claims. (Cl. 122—392)

The present invention refers to soot blowers with a common operating member for the admission of the steam and for rotating the steam pipe provided with one or more nozzles.

The invention relates more particularly to apparatus of this general type in which, upon actuating the operating member, the steam admission valve is first opened and then the steam pipe turned through a predetermined arc, whereupon the steam pipe may be returned to its initial position and the valve then closed. The object of the present invention is to provide a soot blower of this type which is of cheap, simple and reliable construction and in which the opening and closing of the valve and the turning of the spindle or blower tube will be positively brought about in the desired sequence.

This is of importance on many occasions where it is desired to have the effective blowing angle, that is to say the angle at which the blowing takes place with a fully open valve, equal to or nearly equal to a complete revolution.

One form of embodiment of a soot blower or steam sweeping apparatus of this type is illustrated in the accompanying drawing, Fig. 1 is an axial section of the apparatus. Figs. 2, 3 and 4 are cross sections of the spindle of the apparatus and of adjacent parts on the lines 2—2 and 4—4 respectively in Fig. 1, Fig. 3 showing the apparatus in its position of rest with a member pertaining to the operating member turned by half a revolution as against the position according to Fig. 2. Fig. 5 is an endwise view of the apparatus.

In the drawing, the three parts of the casing of the apparatus screwed together are designated by 20a, 20b and 20c. Part 20a surrounds the valve 14 and the steam supply passage 21 which leads to the opening 22 in the spindle or blower tube 6 of the apparatus, which spindle is rotatably mounted in the casing.

Here, the common operating member consists of a sprocket wheel 1 secured to a shaft 2 mounted in the parts 20b and 20c of the casing of the apparatus, said shaft having a gear wheel 3 secured to the inner end thereof, which gear wheel engages a central gear wheel 4 arranged about the spindle 6. This spindle is to be connected in known manner to the nozzle pipe (not shown).

The hub 5 of the gear wheel 4 is rotatably mounted on the spindle 6 of the apparatus, in such a manner that the hub may be turned independently of said spindle, as long as a lug 7 of the spindle is not in contact with either one of two abutting surfaces 8 or 9 in the hub 5, the

spindle 6 being held from rotation at this time by the friction of the parts. The portion of the hub 5 located farthest to the right in Fig. 1 is turned down eccentrically so as to form an eccentric 10. The steam valve spindle 11, which is pressed upwardly by means of a spring 12 and a plate 13, may be depressed by said eccentric 10, so that the steam valve 14 is opened, and may be kept in depressed position by a cam disk 15 made integral with the spindle of the apparatus, in which cam disk is provided a recess 16. Only when this recess is directed downwardly, as shown in the sections illustrated in Figs. 2, 3 and 4, while the eccentric 10 is at the same time situated so that its smallest radius is directed downwardly, as shown in Fig. 3, will it be possible for the valve spindle 11 to come into so high a position that the steam valve can be closed, and is consequently closed. When the apparatus takes this position and the lug or abutment 7 is directed upwardly, the apparatus is in its position of rest, Fig. 3.

The turning of the common operating member, i. e., the sprocket wheel 1, is effected in the usual manner by means of a chain (not shown). When sweeping is to be effected, the sprocket wheel is turned by means of the chain in a clockwise direction, as viewed in Fig. 5, the hub 5 being thus caused to turn in a counter clockwise direction, as viewed in Fig. 3. Until further, this will not bring about any turning movement of the spindle 6, but the recess 16 still remains directed downwardly. However, the valve spindle 11 is urged downwardly by the eccentric 10, so that the valve is brought into its lowermost (fully open) position upon a turning movement of the hub 5 and the eccentric 10 by half a revolution. This position is shown in Fig. 2. On continued turning, the abutment 8 strikes against the lug or abutment 7, so that the spindle of the apparatus (the nozzle pipe) is compelled to participate in the turning movement, which in this manner does not commence, until the steam valve has been fully opened. The turning movement is continued in the same direction, until a pointer arm 17 connected to the spindle 6 strikes against a rigid stop pin 18. Turning is then effected in the opposite direction, the spindle of the apparatus then standing still due to frictional forces, to begin with, until the abutment 9 hits the lug 7. During this manipulation the valve spindle 11 is still kept depressed by the cam 15, and on continued turning, the spindle of the apparatus then participating in the turning move-

ment, the valve is kept open, the blowing thus continuing, until the recess 16 is again directed right downwardly, so that the valve spindle will have an opportunity to move upwardly and the 5 steam valve is consequently closed.

In the apparatus in question, arranged with a stop pin 18, the turning movement will not cover a complete revolution, depending on the thickness of the stop arm 17 as well as of the 10 stop pin.

An effective angle of a complete revolution may be obtained, however, if the stop device 18 is omitted. The procedure of manipulation will then involve turning of the sprocket wheel 1 in 15 a clock-wise direction, as hereinbefore described so that the steam valve 14 is first opened, the spindle of the apparatus being then turned a complete revolution, which is indicated through a suitable designation on a rigid disk 19. Upon 20 a turning movement of a complete revolution, the recess 16 being thus again directed right downwardly, the sprocket wheel is turned in the opposite direction, whereby the eccentric 10 will by degrees permit the valve spindle 11 to rise into 25 its initial position corresponding to the closed position of the steam valve.

A secondary advantage of having the gear wheel hub 5 disengaged from the spindle of the apparatus during a considerable portion of the 30 movements of said hub is to be found in that the member, in this case the eccentric 10, which is to effect the movement of the steam valve has a small pitch, so that a rather small amount of power is required to open the valve, a comparatively 35 small ratio in the operation of the gears being thus rendered possible; the power which is required to open the steam valve is understood to be rather considerable, the whole steam pressure acting on the valve cone.

40 What I claim is:—

1. A soot blower, including a housing, a rotary blower tube having one end journalled in said housing, means for supplying steam to said housing and blower tube, a steam valve for controlling 45 said steam supply, an actuating member loosely and rotatably mounted on the blower tube, means for rotating said member, said member having a portion eccentric to the axis of said blower tube and arranged to open said valve upon rotation 50 of said member, means for automatically closing the valve, a cam disk rigidly mounted on said blower tube and arranged to hold the steam valve open in all angular positions of said cam disk except one, and coupling means for connecting 55 said actuating member to said blower tube to rotate said tube and to move said disk to a position to hold said valve open after the initial rotation of said actuating member has effected the opening of the valve.

2. A soot blower, including a housing, a rotary blower tube having one end journalled in said housing, means for supplying steam to said housing and blower tube, a steam valve for controlling 5 said steam supply, an actuating member loosely and rotatably mounted on the blower tube, means for rotating said member, said member having a portion eccentric to the axis of said blower tube and arranged to open said valve upon rotation of said member, means for automatically closing the valve, a cam disk rigidly mounted on said blower tube and adapted to hold the steam valve open in all angular positions of said disk except one, a projection on said blower tube, and spaced abutments within said actuating member adapted to engage said projection to rotate the blower tube and to move said disk to a position to hold 10 said valve open after said member has rotated an amount sufficient to open said valve.

3. A soot blower, including a housing, a rotary blower tube, having one end journalled in said housing, means for supplying steam to said housing and blower tube, a poppet steam valve within the housing for controlling said steam supply and movable at right angles to the axis of said rotary blower tube, a gear wheel loosely and rotatably mounted on said blower tube, means outside the housing for rotating said gear wheel, the hub of said gear wheel being provided with an eccentric for actuating said poppet valve to open same 20 upon rotation of said gear wheel, means for automatically closing the valve, a cam disk carried by said blower tube and adapted to hold the steam valve open in all angular positions of said disk except one, and coupling means for connecting 25 said gear wheel to said blower tube to rotate said tube and move said cam disk to a position to hold said valve open after said gear wheel has rotated an amount sufficient for said eccentric to open 30 said valve.

4. A soot blower, including a housing, a rotary blower tube journalled in said housing, means for supplying a blowing medium to said blower tube, a valve for controlling the supply of said medium, means to open said valve and to rotate 45 said blower tube, said means comprising two cam disks actuating said valve, one cam disk being loosely and rotatably mounted on said blower tube and arranged to open said valve whereas the other cam disk is rigidly connected with the said tube and arranged to hold said valve open after said loosely mounted disk has opened the same, coupling means for connecting said cam disks after the loosely mounted cam disk has been moved a sufficient amount to open the valve, and operating means for rotating said loosely mounted disk to cause opening of the valve before the blower tube is rotated.

CARL AXEL ARVID WESTERBERG.
